UNITED STATES PATENT OFFICE.

HAROLD CORNELIUS READING, OF DEWSBURY, ENGLAND.

INTERNAL-COMBUSTION ENGINE.

1,398,647.

Specification of Letters Patent. Patented Nov. 29, 1921.

Application filed March 31, 1920. Serial No. 370,182.

To all whom it may concern:

Be it known that I, HAROLD CORNELIUS READING, a subject of the King of Great Britain, residing at Union Bank Chambers, Dewsbury, in the county of York, England, have invented certain new and useful Improvements in or Relating to Internal-Combustion Engines, of which the following is a specification.

10 This invention comprises certain improvements in or relating to internal-combustion engines, particularly of the two-stroke type.

The present invention comprises an internal-combustion engine, in which explosive mixture is introduced into a chamber from which it is injected by a part moving with the piston into the explosion space to admix therein with air, advantageously admitted to said explosion space for pre-compression.

20 This function is advantageously attained by the utilization of a pump element moving with the piston adapted to induce a charge and to inject the charge through a non-return valve into the explosion chamber. The said

25 pump element advantageously comprises a sleeve-like extension of the cylinder, and the ingress of the explosive mixture to the pump may take place through a non-return valve or through ports opened by the operation of the pump.

In order that this invention may be clearly understood and readily carried into practice, reference may be had to the appended explanatory drawings, 35 upon which:—

Figure 1 illustrates in sectional elevation an embodiment of the present invention.

Fig. 2 illustrates in sectional elevation a modified embodiment of the present invention.

Fig. 3 illustrates in sectional elevation a further modification of the invention.

Fig. 4 illustrates in sectional elevation a still further modification of the invention.

45 In a convenient embodiment of the present invention, and referring to Fig. 1, the main explosion chamber *a* is adapted to receive pure air from the crank chamber; into this pure air, rich mixture is adapted 50 to be injected by a compression system operating by virtue of a stepped piston. To this end the ordinary piston *b* is at its end face provided with a sleeve-like extension *c* which works within a sleeve-like extension *d* of the cylinder head. The cylinder head also carries a fixed sleeve *e* which works within the

sleeve of the piston; this fixed sleeve may carry piston rings *f* working in relation to the internal surface of the piston sleeve. Within its sleeve the piston carries a projection *g* which may be in the nature of a closed hollow cone or elongated thimble; this projection is adapted to move into and out of a similar thimble *h* fitted in the fixed sleeve of the cylinder. This last-mentioned 60 thimble is, however, at its end remote from the piston placed in communication with the cylinder through a transfer passage controlled by a non-return valve *i*. The carburetor is in communication with the outermost extremity of the fixed sleeve. Ports *j* are provided at or near the innermost extremity of this fixed sleeve, and in the transfer passage between the fixed thimble and the combustion chamber communication is 65 provided with the annular space *k* in which the moving sleeve works. Upon the suction stroke, therefore, vacuum is created in the fixed thimble *h* and also in the annular space *k* in which the moving sleeve works. 70 As soon as the moving sleeve uncovers the ports *j* in the fixed sleeve, rich mixture from the carburetor passing through the interior of the fixed sleeve is enabled to flow through the ports into the annular passage and to 75 find its way into the fixed thimble *g*. Upon the compression stroke this charge is trapped, compressed within the fixed thimble by the moving thimble, and also by 80 the moving sleeve; by this means rich mixture is injected through the non-return valve *i* into the explosion space *a*, in which pure air resides under a less pressure than that under which the rich mixture has been 85 injected. The ultimate mixture is fired in 90 the region at which the rich mixture is injected to produce the power stroke. Upon completion of this power stroke an exhaust opening is uncovered in the cylinder wall, and a transfer port is also uncovered to 95 admit pure air from the crank chamber. Since the precompressing of this pure air in the crank chamber takes place over the entire area of the piston, and since the said pure air is transferred to the explosion 100 space, which does not occupy the entire area of the piston, an effective scavenging is obtained with a substantial quantity of pure air.

105 The non-return valve *i* controlling the transfer passage from the fixed thimble to the explosion space may comprise a conical

valve having a sleeve *l* working upon a projection *m*, so that the said sleeve contains an air cushion, this air cushion, as well as a suitable coiled spring *n*, being adapted to 5 retain the valve in relation to its seat.

In the modified embodiment of the invention illustrated in Fig. 2, the piston is provided with a sleeve extension *o* adapted to work within an extension *p* of the cylinder. 10 With this extension *p* of the cylinder the carbureter is placed in communication by way of the non-return valve *q* which may resemble that designated *i* in Fig. 1. In the down-stroke of the piston, rich mixture is 15 induced into the space *r*, and upon the up-stroke of the piston this rich mixture is injected by way of ports *s*, the non-return valve *t* (which again may resemble that designated *i* in Fig. 1) and the conduit *u* into the explosion space *v* by way of orifices *w*. In this illustration, *x* is the exhaust opening, and *z* the transfer passage for the precompressed air charge into which the rich mixture from the conduit *u* is injected. 20 The modification illustrated in Fig. 3 is similar to that illustrated by Fig. 1, with the exception that the thimble *g* of the last-mentioned figure is omitted.

For this reason, reference letters have 30 been placed upon Fig. 3 corresponding with those which have been utilized in Fig. 1.

Fig. 4 illustrates in part a modification of the parts shown in the preceding figures. In this embodiment 3 is the sleeve-like extension of the piston working within the sleeve-like extension 4 of the cylinder, and around the fixed sleeve 5, the interior of which is in communication with the carbureter. At or near the conclusion of the down stroke of 40 the piston, the carbureter is placed in communication with the interior of the sleeve 3 by a series of ports 6 provided at or near the uppermost extremity of said sleeve. Upon the up-stroke of the piston the charge 45 within the sleeve 3 is trapped, and said trapped charge is injected into the explosion space through a non-return valve 7 by way of a port or ports 8. These ports may be so arranged at varying heights that when there 50 is a free charge within the sleeve 3 the mixture is discharged through all of the ports, whereas in the case of a partial charge the valve 7 is not displaced in the same degree, with the result that only the port in proximity to the sparking-plug is uncovered. The ports 8 may, if desired, be located at an angle, if necessary, to provide for the thorough mixing of the mixture with the air charge. The valve 7 may have a pneumatic 55 cushion as described in connection with the valve *i* of Fig. 1, and if desired a tension spring 9 may be provided and arranged to

tend to retain the valve 7 in relation to its seating. One extremity of this spring may be retained within a groove 10 in the bottom 65 of the valve 7, while the other extremity may rest upon a ledge 11 occurring above the seating of the valve.

Any combination of the ingress and egress arrangements for the mixture shown in the 70 several modifications may, alternatively, be utilized.

What I claim as my invention and desire to secure by Letters Patent is:—

1. In an internal combustion engine having a carbureter, a cylinder having a combustion chamber and an extension and a conduit arranged for connection to the carbureter and leading from said extension to the combustion chamber of the cylinder, a valve in said conduit arranged to close against pressure from the combustion chamber, and a piston in the cylinder and having means to draw a rich mixture into the said extension at its outstroke, and at its instroke 85 to force said rich mixture through said conduit into said combustion chamber.

2. In an internal combustion engine having a carbureter, a cylinder having a combustion chamber and an extension and a conduit arranged for connection to the carbureter and leading from said extension to the combustion chamber of the cylinder, a valve in said conduit arranged to close against pressure from the combustion chamber, and a piston in the cylinder, having an extension 90 arranged to open said conduit and draw a rich mixture into the extension of the cylinder at an outstroke of the piston, and at an instroke of the piston to force said rich mixture through said conduit into said combustion chamber and then close said conduit.

3. In an internal combustion engine having a carbureter, a cylinder having a combustion chamber and an extension and a conduit arranged for connection to the carbureter and leading from said extension to the combustion chamber of the cylinder, a valve in said conduit arranged to close against pressure from the combustion chamber, and a piston in the cylinder, having a hollow cylindrical extension arranged to open said conduit and draw a rich mixture into the extension of the cylinder at an outstroke of the piston, and at an instroke of 105 the piston to force said rich mixture through said conduit into said combustion chamber and then close said conduit, said cylinder extension having an annular space communicating with said conduit and in which 110 said piston extension operates.

In witness whereof I have hereunto set my hand.

HAROLD CORNELIUS READING.
